(57) **CLAIM**

The ornamental design for a camera, as shown and described.

DESCRIPTION

FIG. 1 is a perspective view of a camera showing the front, right, and top sides of our design;
FIG. 2 is an elevation view showing the front side of our design;
FIG. 3 is an elevation view showing the rear side of our design;
FIG. 4 is an elevation view showing the left side of our design;
FIG. 5 is an elevation view showing the right side of our design;
FIG. 6 is a plan view showing the top side of our design; and,
FIG. 7 is a plan view showing the bottom side of our design.
It should be understood that the labels used herein for describing orientation (e.g., front, back, top, bottom, right, and left) are merely for Reference, and views of the design may be disposed in any manner and still be within the scope of the present invention. The portions of the article in broken lines are shown for illustrative purposes only and form no part of the claimed design.
